UNITED STATES PATENT OFFICE.

BENJAMIN WOLHAUPTER, OF NEW ROCHELLE, NEW YORK, ASSIGNOR TO THE RAIL JOINT COMPANY, OF NEW YORK, N. Y., A CORPORATION OF NEW YORK.

ABRASION UNIT FOR RAIL JOINTS.

Application filed October 13, 1922. Serial No. 594,285.

To all whom it may concern:

Be it known that I, BENJAMIN WOLHAUPTER, a citizen of the United States, residing at New Rochelle, in the county of Westchester and State of New York, have invented certain new and useful Improvements in Abrasion Units for Rail Joints, of which the following is a specification.

This invention relates to rail joints, and has particular reference to an improved abrasion unit having novel features of construction and design that render it of special utility in connection with standard types of joint or splice bars having a wedge fit in the fishing space of the rail, thereby to compensate for the wear which is usually focused on the bearing faces of the bars at or near the rail ends.

A primary object of the invention is to provide a simple, practical and reliable construction to compensate for the wear usually imposed on the joint bars, thereby materially increasing the life of the joint.

To that end the invention contemplates a relatively thin hard metal abrasion unit or wear filler including members adapted for engagement with the underside of the rail head and the upper side of the base flange of the rail, and possessing adequate strength to withstand the loading strain to which the joint bars are subjected by the passing wheel loads. Also, the improved unit or filler is intended to sufficiently adapt or adjust itself vertically to permit of the splice bar properly drawing the rail bearing members thereof against the head and base flange of the rail without undue friction when the bar is pulled into place by the joint bolts. That is to say, as wear occurs, and the joint bolts are tightened to draw the splice bars further into the fishing spaces of the rails, the rail bearing members of the abrasion unit will firmly and evenly engage the rails without binding and without friction due to the special formation of the medial portion of the vertical web of the unit which adequately provides for the diminution or contraction of the vertical height of the unit as the latter is moved into the converging fishing spaces of the rails.

A further and important object is also to provide a metal abrasion unit designed and formed to permit of the shifting of the entire member longitudinally in either direc-

tion between the rail and bar head as wear occurs, thereby materially adding to the life of the unit by bringing the least worn portions thereof into use.

With the above and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawings, in which:—

Figure 1 is a side elevation of a portion of the improved abrasion plate in position at the rail ends, the splice bar being indicated by dotted lines.

Figure 2 is a bi-sected vertical sectional view taken on the line 2—2 of Figure 1.

Figure 3 is a side elevation of a pair of adjoining rail ends with the joint bar removed showing the improved abrasion plate in one of its positions.

Figure 4 is a view similar to Figure 1 illustrating another adjusted position of the abrasion plate.

Similar reference characters designate corresponding parts throughout the several figures of the drawings.

One of the distinctive features of the invention is to provide an abrasion unit of relatively thin hard metal to be clamped between the splice bars and the rails for relieving the head and foot portions of the bars or equivalent members from direct wearing contact with the rails, thereby protecting the joint bars from the usual chafing action imposed thereon due to the movement of the rail itself under passing wheel loads, and materially lengthening the life of the joint.

According to the practical embodiment shown in the accompanying drawings it is proposed to provide a structure possessing novel features of construction and design for carrying the foregoing desired objects into effect. That is to say, it is proposed to provide a wear filler of substantially channel formation whereby the top and bottom flange members of thin hard metal for the head and foot of the joint or splice bar are connected by an intermediate web portion which yields or otherwise compensates for the movement of the head and foot por-

tions of the bar inwardly under the tightening action of the joint bolts.

In the embodiment shown the abrasion unit or wear filler is designated generally as 5 A, and the upper and lower bearing members or chafing flanges 1 and 2 are connected by a vertical web 3, the said unit being of substantially uniform thickness throughout.

As will be observed from Figure 2 of 10 the drawings, the web portion 3 possesses adequate resiliency to bow or flex as the bearing members or flanges 1 and 2 are forced into contact with the converging walls of the fishing space of the rails R, thereby relieving the bearing members of 15 the friction which would otherwise be caused if the web were rigid and the bearing members forced into a binding instead of a supporting engagement with the rails. The 20 vertical resiliency of the web 3 in this form of the invention is materially increased by the formation of the relatively large central opening 4 and the relatively flaring openings 5 and 5^a located at the ends of the web, together with the outer and inner sets of bolt 25 clearance openings 6 and 7 respectively which leave only a relatively small connecting strip 8 forming the integral part of the web.

30 In connection with the bolt receiving openings 6 and 7, above mentioned, another important and distinctive feature of the invention exists. That is to say, the abrasion unit A is somewhat of greater length than 35 the joint bar B so that the ends thereof will project beyond the ends of the bar in the normal set position of the unit, and when the unit is shifted either to the right or to the left within the range permitted by the openings for the joint bolts the flanges 1 and 2 will still adequately protect the joint bars 40 from engagement with the rail.

In making the desired adjustment of the abrasion unit, the joint bolts C', C², C³ and 45 C⁴ must be removed and the entire unit shifted to the desired position, whereupon the bolts may be replaced in openings which register with the bolt positions and again be tightened to lock the unit in the desired 50 adjusted position and prevent accidental slipping or creeping thereof under the action of passing wheel loads.

Assuming that the normal set position 55 of the abrasion unit A is shown in Figure 1, it will be observed from Figure 3 that if the unit is shifted the maximum distance to the right, the joint bolt C² will rest in the opening 7^a while the joint bolt C' will be disposed in the flared open end 5 of the unit 60 and the bolt C⁴ will rest in opening 6^b. On the other hand if the unit is shifted to the maximum distance to the left, as shown in Figure 4, the joint bolt C' will be positioned in the opening 6^a while the joint bolt C² will be disposed in the large central open-

ing 4. The bolt C³ will then be disposed in the opening 7^b and the bolt C⁴ will be located in the flared open end 5^a of the unit. In this case the bolts C' and C³ hold the unit in adjusted position and in all adjustments 70 at least two bolts are engaged with the web.

Obviously, intermediate adjustments between the extreme right and left may be effected by placing the joint bolts in the middle openings of each set. In the particular arrangement shown the filler is capable of five adjustments, namely, the original set position shown in Figure 1 and two positions to the left, and two positions to the right, thereby making it possible to bring five different areas of the members 1 and 2 into contact with different portions of the rail.

From the foregoing it will be apparent that a novel and distinctive feature of the present invention is to provide an abrasion 85 unit or wear filler of relatively thin hard metal, the vertical portion of which is constructed to compensate for the relative contraction in the height thereof as the same is drawn further into the fishing space of the 90 rails upon the tightening of the joint bolts. In other words, it is proposed to provide an abrasion unit whose vertical height is relatively adjustable, and which is also adjustable longitudinally as a whole between the 95 bar and the rails, thereby obtaining a wide range of adjustment which enables the invention to meet practically all conditions of use in a thoroughly practical and efficient manner.

Without further description it is thought that the features and advantages of the invention will be readily apparent to those skilled in the art and it will of course be understood that changes in the form, proportion and minor details of construction may be resorted to without departing from the spirit of the invention or scope of the appended claims.

I claim:—

1. In a rail joint, the combination with the joint bar and the rail ends, of a longitudinally adjustable metal plate adapted to have a bearing between the bar and the rail.
2. In a rail joint, the combination with the joint bar and the rail ends, of a longitudinally adjustable metal plate adapted to furnish a plurality of wear faces beneath the rail ends.
3. In a rail joint, the combination with the joint bar, of a thin hard metal abrasion plate of substantially uniform section throughout and having an open part to produce a vertically resilient web portion.
4. In a rail joint, the combination with the joint bar, of a thin hard metal abrasion plate adapted to be clamped between the bar and the rail, said plate being of substantially channel formation to provide flanges for engaging with the rail head and rail

base, and the web of the plate having openings located at the center and end portions thereof to produce vertical resiliency in the plate.

5 5. In a rail joint, the combination with the joint bar, of a thin hard metal abrasion plate of channel cross section and substantially uniform thickness throughout, the web portion being provided with openings 10 to provide vertical resiliency for the plate and also permit the longitudinal shifting thereof between the joint bar and the rail.

6. In a rail joint, the combination with the joint bar, of a thin hard metal abrasion 15 plate of channel formation and substantially uniform thickness throughout, the web portion of said plate being provided with an enlarged central opening and openings at the end thereof to provide vertical resiliency for the plate, and said web also being provided with other openings for accommodating the joint bolts when the plate is shifted longitudinally between the bar and the rail.

20 25 7. In a rail joint, the combination with the joint bar and the rail ends, of a longitudinally and vertically adjustable metal plate adapted to have a bearing between the bar and the rail.

30 8. In a rail joint, the combination with

the joint bar and the rail ends, of a longitudinally adjustable metal plate adapted to have a bearing between the bar and the rail and provided with openings in the web to provide vertical resiliency for the plate. 35

9. In a rail joint, the combination with the joint bar and the rail ends, of a longitudinally adjustable metal plate adapted to furnish a plurality of wear faces between the rail ends and provided with openings 40 in the web to provide vertical resiliency for the plate.

10. In a rail joint, the combination with the joint bar of a thin, hard metal abrasion plate fitted in the fishing space of the 45 rail and adapted to be shifted longitudinally therein between the bar and the rail and provided with openings to provide vertical resiliency for the plate.

11. In a rail joint, the combination with 50 a joint bar, of a thin hard metal abrasion plate fitted in the fishing space of the rail and adapted to be shifted longitudinally therein between the bar and the rail.

In testimony whereof I hereunto affix my 55 signature in the presence of two witnesses.

BENJAMIN WOLHAUPTER.
